No. 12, 706

Jan. 24, 1882

UNITED STATES PATENT OFFICE.

OLIVER B. KEELEY, OF SPRING CITY, PENNSYLVANIA.

DESIGN FOR A COOKING-STOVE.

SPECIFICATION forming part of Design No. 12,706, dated January 24, 1882.

Application filed December 19, 1881. Term of patent 7 years.

To all whom it may concern:

Be it known that I, OLIVER B. KEELEY, a citizen of the United States, and a resident of Spring City, Chester county, Pennsylvania, have invented a Design for a Cooking-Stove, of which the following is a specification.

My design for a cooking-stove is fully shown in the accompanying drawing.

The main oven-door A of the stove is of the usual L shape, and its principal ornament is an oblong panel, a, surmounted at one end by a pyramidal structure, b. The door has the usual rounded edge and border and minor ornamentation, d.

15 The small doors B of the fire-place and warming closet and the panel B' at the end of the water-reservoir have rounded edges and borders, and each has a central pyramidal ornament, e.

20 The skirting D has a central ornament, f, and side ornamentation, g.

The front fire-door, F, has a longitudinal panel, h, and three upright windows, i.

I claim—

1. The design for the oven-door A, said design comprising essentially the oblong panel a and the pyramidal structure b, surmounting one end of the panel, all substantially as shown and described. 25

2. The design for the doors and panel B B', said design comprising the border and the central pyramidal ornament, e, as shown and described. 30

3. The design for the skirting D, said design comprising the central ornament, f, and side 35 ornamentation, g, as shown and described.

4. The design for the complete structure, comprising the doors A B, panel B', skirting D, and fire-door F, all ornamented as shown and described. 40

In testimony whereof I have signed my name to this specification in the presence of two subscribing witnesses.

OLIVER B. KEELEY.
